(57) **CLAIM**

The ornamental design for a nebulizer, as shown and described.

DESCRIPTION

FIG. 1 is a perspective view of a nebulizer, showing our new design.

FIG. 2 is a left side view thereof.

FIG. 3 is a bottom view thereof.

FIG. 4 is a front elevational view thereof.

FIG. 5 is a rear elevational view thereof.

FIG. 6 is a perspective view thereof, shown with the extension tube removed.

FIG. 7 is a left side view thereof.

FIG. 8 is a bottom view thereof.

FIG. 9 is a front elevational view thereof.

FIG. 10 is a rear elevational view thereof.

FIG. 11 is perspective view similar to that shown in FIG. 1, with the vent tube removed therefor.

FIG. 12 is a left side view thereof.

FIG. 13 is a bottom view thereof.

FIG. 14 is a front elevational view thereof.

FIG. 15 is a rear elevational view thereof.

FIG. 16 is a perspective view similar to that shown in FIG. 1, with the extension tube and the vent tube removed.

FIG. 17 is a left side view thereof.

FIG. 18 is a bottom view thereof.

FIG. 19 is a front elevational view thereof; and,

FIG. 20 is a rear elevational view thereof.
